SIGNAL TRANSMITTING AND RECEIVING
SYSTEMWinfield R. Koch, Merchantville, N. J., assignor to
Radio Corporation of America, a corporation of
Delaware

Application June 22, 1937, Serial No. 149,621

4 Claims. (Cl. 250—20)

This invention relates to signal transmitting and receiving systems such as are useful in hearing aids for the deaf or in cases where a listener frequently moves from one location to another, and has for its principal object the provision of an improved apparatus and method of operation whereby the weight and complexity of the equipment required to be carried by a moving listener is greatly reduced.

10 Further objects of the invention are the provision of (1) an improved apparatus for making radio programs readily heard by the deaf, (2) an improved short wave receiver including means for automatically maintaining its volume at a predetermined level irrespective of movement of the listener or others in his vicinity and (3) a simple and compact transmitting and receiving system which may be readily utilized either as an adjunct to the ordinary radio receiver or as a desk unit for the transmission of intelligence to the deaf.

More particularly, the invention contemplates the provision of micro-wave transmitter connected to the output of an ordinary radio receiver and a micro-wave receiver adapted to be carried by the listener. In the operation of a system of this character, it is found that movement of the listener or movement of others in the vicinity of the listener produces in the field pattern at the receiver variations which adversely affect the received sound. This difficulty is avoided in accordance with the present invention by the provision of improved means for automatically suppressing such variation. As will hereinafter more fully appear, the volume variation suppression means may assume the form of (1) a volume leveling device such as a biased crystal detector or, (2) a micro-ammeter controlled variometer shunted across the telephone receiver.

40 The invention will be better understood from the following description when considered in connection with the accompanying drawing and its scope is indicated by the appended claims.

Referring to the drawing,

45 Figure 1 is a wiring diagram of a portable micro-wave receiver including a volume leveler of the biased crystal detector type,

Figure 2 is a similar diagram of a combined radio receiver and micro-wave transmitter, and

50 Figure 3 illustrates the use of an ammeter controlled variometer for volume leveling.

The portable receiver of Fig. 1 includes an antenna 10 which is connected to a telephone head set 11 through a tuned circuit 12 and a crystal detector 13. For the purpose of automatically

leveling the volume of the signal at the receiver 11, there is connected in shunt to this signal channel a crystal detector 14 and a bias potential source or battery 15. It will be noted that this receiving unit is very small and compact and that the only battery necessary for its operation is the delay battery 15 which is subject only to charging current instead of discharging current. This battery is therefore very small and operates satisfactorily for very long periods of time, the power consuming parts all being located at the micro-wave transmitter associated with the radio receiver output or other transmitting unit.

The combined receiver and transmitter of Fig. 2 includes a radio receiver 16 which is coupled through a transformer 17 to a loudspeaker 18. Also connected to the secondary winding of the output transformer 17 is a short wave transmitter comprising a short wave oscillator generator 19 which has its input and output circuits intercoupled through a concentric line 20—21 and is coupled through this line to an output antenna 22. Interposed between the transformer secondary are an impedance device 23 and a switch 24 for segregating the transmitter when it is not in use.

The short wave receiver of Fig. 3 is similar to that of Fig. 1 in several respects but differs therefrom in that the biased crystal detector is replaced by a variometer 25 which is automatically operated by an ammeter mechanism 26 in response to the detected output of the receiver. The tuned circuit is resonant to the signal with the variometer in the position it assumes for weak signals. Strong signals produce a greater rectified current through the ammeter movement, changing the position of variometer 25, which in turn causes a de-tuning of the circuit through the change in inductance. This de-tuning keeps the radio frequency voltage applied to the crystal detector from becoming unduly large. It will be observed that this receiver does not involve the use of any batteries and will therefore be of very light weight, and long life.

I claim as my invention:

1. In a hearing aid system, the combination of a portable short wave radio receiver including an antenna, a variometer, a crystal detector, a telephone receiver connected to said antenna through said detector and said variometer, and volume leveling means connected in series with and operable in response to the current of said telephone receiver to detune said variometer.

2. In a hearing aid system, the combination of a portable short wave radio receiver including

an antenna, a crystal detector, a telephone receiver connected to said antenna through said detector, and volume leveling means including a variometer connected in shunt to said telephone receiver and means for automatically adjusting the impedance of said variometer in response to the current of said telephone receiver.

3. In a receiving system, the combination of a variometer and means for varying the impedance of said variometer, a motor, a detector and a telephone receiver serially connected between points intermediate the ends of said variometer, said motor being responsive to rectified currents from said detector and operatively connected to said

impedance varying means for automatically adjusting the impedance of said variometer.

4. In a high frequency receiving system, the combination including a variometer consisting of an inductor and a metallic disc movable in the plane of said inductor, a motor, a detector and a telephone receiver serially connected between points intermediate the ends of said variometer, said motor being responsive to rectified currents from said detector and operatively connected to 10 said metallic disc for automatically moving said disc to control the amplitude of said rectified current.

WINFIELD R. KOCH.
